FIG. 6

UNITED STATES PATENT OFFICE

2,566,761

HEARING AID

William Dubilier, New Rochelle, N. Y.

Application December 7, 1948, Serial No. 63,921

3 Claims. (Cl. 179—107)

1
My present invention relates to hearing aids and more particularly to a compact simplified composite microphone structure for a hearing aid wherein a single microphone casing contains the current supply and all other elements of the hearing aid, except the ear phone connected thereto.

The primary object of my present invention is the utilization in connection with the microphone portion of the hearing aid of a novel type of spring wound variable resistor so arranged that when it is compressed or expanded longitudinally the coils of the spring separate or are brought together successively and not simultaneously; for each separation between adjacent turns of the spring wound resistor a full turn of the resistor is introduced in the circuit, and for each contact between two turns, a full turn of the spring is eliminated or shunted out of the circuit.

Another object of my invention is to utilize in connection with a microphone of the foregoing type a conically wound resistor spring so arranged that as volume peaks are reached beyond a desirable amplitude, successively smaller turns of the resistor spring are introduced into and shunted out of the circuit.

Another object of my invention is the provision and utilization of a circular or doughnut shaped battery in the microphone housing or casing as the source of current supply, the center opening in the said battery providing a recess in which the spring or the housing for the resistor spring may be received.

My invention contemplates mounting a microphone diaphragm so that its vibrations will compress and expand the spring, varying the resistance of the resistor spring.

The resistor spring, the battery, and the ear piece are connected in series so that variations in the resistance of the spring will result in variations in current flow to the ear piece and thereby vary the intensity of the vibrating element in the ear piece which may be of a standard type in accordance with the amplitude variations in the current, which in turn result from the amplitude variations of the microphone diaphragm; and, of course, the frequency of the vibrations of the vibrating element in the ear piece will correspond to the frequency of the vibrations of the diaphragm in the microphone.

The foregoing and many other objects of my invention will become apparent in the following description and drawings in which:

Figure 1 is a vertical cross-sectional view through my novel composite microphone forming a hearing aid.

2
Figure 2 is an exploded view of the hearing aid of Figure 1.

Figure 3 is an elevation of a portion of the main housing of the unit of Figure 1 taken from line 3—3 looking in the direction of the arrows.

Figure 4 is an elevation of the battery to be utilized in connection with the unit of Figure 1.

Figure 5 is a schematic view showing the circuit diagram of the unit of Figure 1.

Figure 6 is an enlarged view of the spring resistor of Figure 1.

Referring now to the figures, the composite hearing aid housing 10 is an annular structure of insulating material having the bell-shaped front wall 11 which defines with the annular wall 10 the annular chamber 12. The mouth of the bell-shaped front wall 11 is provided with an annular ledge 13 against which the diaphragm 14 may be seated.

10 The diaphragm 14 is then held in position by the ring clamping cover 15 having the internal ledge 16 which seats against the diaphragm and the threads 17 which engage the thread 18 on the front of the annular wall 10.

20 The closed rear portion 20 of the bell-shaped wall 11 extends up to or beyond the rear portion of the annular wall 10 and is provided with the threaded insert 21 which receives the adjustment screw 22, the adjustment screw 22 being longitudinally movable therein by small increments as it is rotated.

25 The resistor spring 25 has one end 26 thereof soldered in the notch 27 of the adjustment screw 22 and the other end 28 of the resistor spring 30 is soldered to the wire 29 attached at the center of the diaphragm. Vibrations of the diaphragm will thus result in longitudinal vibrations of the resistor spring 25 to vary its resistance in accordance with the amplitude of the vibrations of 35 the diaphragm 14 at a frequency which will correspond to the frequency of the vibrations of the diaphragm 14.

30 A sponge rubber or other soft snubbing element 20, 30, preferably of a shape to correspond to 45 the interior shape of the resistor spring 25 is inserted in the spring 25 to prevent extraneous vibrations of the spring 25 so that all vibrations thereof will be in response only to vibrations of the diaphragm 14.

40 A circular or doughnut shaped battery 32 having the circular recess 33 is provided, the said battery having the usual electrodes and electrolyte and being so shaped that it fits within the annular chamber 12 formed by the two walls 10 50 and 11. The circular opening 33 in battery 32 fits over the bell-shaped wall 11 so that the rear

portion 20 projects beyond the battery, thereby making the adjustment screw 22 accessible.

A cover 35 having a thread 36 and a circular opening 37 is mounted on the rear end of the annular wall 10 with the thread 36 interengaging with the thread 40 of the wall 10 to secure the battery in place. The circular opening 37 in the cover 35 provides clearance for the rear end 20 of the bell-shaped wall 11 so that the adjustment screw 22 is always accessible even while the unit is closed.

To replace the battery, it is then necessary only to remove the cover 35, remove the battery, insert the new battery, and replace the cover 35.

If desired, appropriate spring means may be mounted on the interior of cover 35 to hold the battery tightly in position. The annular wall 10 of the unit may be provided on its interior with the key 42 which rides in the keyway 43 of the battery 32 so that the battery may be inserted 20 at only the exactly correct angular position to make proper contact.

The battery is provided with two contact elements 50, 51 in a manner well-known in the art connected to the electrodes of the battery and, of course, insulated from each other. The end 28 of the spring is connected to the wire 55, preferably being soldered thereto or in any other suitable manner.

The wire 55 is, of course, a highly flexible wire permitting free vibration of spring 25. Wire 55 is soldered to the metal insert 56 which passes through wall 11 of the housing. Wire 57 is soldered to the opposite end of the metal insert 56 and passes through the wall 10 to be connected to wire 58 leading to the ear piece 60.

The other end 26 of the spring resistor 25 is soldered to the flexible wire 61, which in turn is connected to the metal insert 62 passing through the wall 11. The opposite end of the metal insert 62 has connected thereto the wire 63 which is connected to the stationary contact 64, which preferably is a spring biased contact member.

Contact 64 engages the electrode contact 51 of the battery 32. Electrode 50 of the battery 32 engages contact 65 which is a contact similar to the contact 64 but is, of course, insulated therefrom.

Contact 65 is connected by wire 66 which passes through the wall 10 to wire 67 connected to the ear piece 60.

Thus, as seen in Figure 5, as well as in Figures 1 and 2, the circuit for energizing the ear piece 60 is from terminal 51 of the battery 32 to stationary contact 64 in the housing, then through wire 63, metal insert 62, wire 61, through the spring resistor 25, then through wire 55, metal insert 56, wire 57, wire 58 to the ear piece 60, then through wires 67 and 66 back to contact 65 in engagement with terminal 50 of the battery.

Vibrations of the diaphragm 14 will result in corresponding longitudinal vibrations of the spring resulting further in varying the resistance of the spring 25 in accordance with the amplitude of the vibrations of diaphragm 14, at a frequency corresponding to the frequency of the vibrations of diaphragm 14.

The amplitude and frequency of the current passed through the ear piece 60 will thus be a function of the amplitude and frequency of vibrations of diaphragm 14.

Since resistor springs of the type of spring 25 may be made extremely small, the resistor spring 25 may be as small as $\frac{3}{8}$ of an inch long and even

less, and all other parts of the unit may be correspondingly small.

The circular battery which fills all of the space in the unit 10, except for the space occupied by the spring resistor 25, provides a single battery having an effective size much greater than any previously possible for use in such small spaces.

Thus, although the entire unit need not be more than one inch or one inch and a half in diameter, the provision of a circular battery makes possible an outer electrode having the area of a battery three or more inches long and an inner electrode of corresponding length, together with the provision of space for such electrolyte to render the battery as efficient in operation as a straight battery of the order of three inches long.

Thus, the combination of the resistor spring and the circular battery make possible the creation of a small compact hearing aid unit, the full dimensions of which (aside from the ear piece and its cord) need be not more than 1 to 1.5 inches in diameter and not more than .5 to 1 inch in thickness.

The utilization of my novel circular battery makes possible also the utilization of other types of variable resistance elements for use in connection with a diaphragm.

Thus, instead of the spring resistor 25, a bare resistance wire may be wound over insulation around a magnetic core. The turns of the wire may then be bridged by a highly conductive ferrous strip normally biased smoothly against the wire by the magnetic core. One end of the strip, however, is lifted away from the turns of the wire and secured to the center of the diaphragm. Vibrations of the diaphragm will cause the conductive strip to bridge more or fewer turns of the resistance wire in accordance with the amplitude of the vibrations of the diaphragm, thereby varying the resistance of the resistance wire proportionally to the amplitude of the vibrations of the diaphragm and at a frequency corresponding to the frequency of the diaphragm.

The resistance wire may then be connected in the circuit in the same manner as that described in connection with Figures 1 to 5 as a substitute for the spring resistor 25.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A hearing aid comprising microphone, a housing therefor, said microphone including a diaphragm, a variable electrical resistance member, a mechanical connection between said resistance member and said diaphragm for varying the electrical resistance of said member in response to vibration of said diaphragm; said housing having an annular chamber for supporting a battery surrounding said microphone, and an annular battery within said chamber.

2. A hearing aid comprising a microphone including a diaphragm and a variable electrical resistance member comprising a resilient conical wire helix, the turns thereof being successively movable into and out of engagement with each other to vary the electrical resistance thereof; a mechanical connection between said resistance member and said diaphragm for varying the elec-

trical resistance of said member in response to vibration of said diaphragm.

3. A hearing aid comprising a microphone including a diaphragm and a variable electrical resistance member comprising a resilient conical wire helix, the turns thereof being successively movable into and out of engagement with each other to vary the electrical resistance thereof, a mechanical connection between the base end of said helix and said diaphragm for varying the 10 electrical resistance of said member in response to vibration of said diaphragm.

WILLIAM DUBILIER.
